The ornamental design for a locking burr for interlocking fasteners, as shown and described.

DESCRIPTION

FIG. 1 is a perspective view of a locking burr for interlocking fasteners showing my new design;

FIG. 2 is a top plan view thereof;

FIG. 3 is a first side elevational view thereof;

FIG. 4 is a second side elevational view thereof as seen 90° from that of FIG. 3;

FIG. 5 is a third side elevational view thereof as seen 90° from that of FIG. 4;

FIG. 6 is a fourth side elevational view thereof as seen 90° from that of FIG. 5; and,

FIG. 7 is a bottom plan view thereof.
